UNITED STATES PATENT OFFICE.

JESS CLAIR KELLY, OF CAMBRIDGE, OHIO.

DESIGN FOR A CANDLESTICK.

Application filed January 25, 1929. Serial No. 29,770. Term of patent 3½ years.

To all whom it may concern:

Be it known that I, JESS CLAIR KELLY, a citizen of the United States, residing at Cambridge, in the county of Guernsey and State of Ohio, have invented a new, original, and ornamental Design for Candlestick, of which the following is a specification, reference being had to the accompanying drawing, forming part thereof.

Fig. 1 is a front elevation of a candlestick showing my new design;

Fig. 2 is a top plan view, and

Fig. 3 is an end elevation.

I claim:—

The ornamental design for a candlestick as shown.

J. CLAIR KELLY.
